UNITED STATES PATENT OFFICE

DANA M. CARMER, OF PHILADELPHIA, PENNSYLVANIA

STOCKING

Application filed April 10, 1931. Serial No. 529,159.

This invention relates to full-fashioned hosiery, and more particularly to improvements in the design and construction of the upper or welt portion of the stocking.

Those familiar with the art to which the present invention appertains have always appreciated the fact that hose supporters of the type now generally employed are decidedly injurious to silk stockings in that the clasp thereof, even though free from rough surfaces, exerts a severe strain and pull on the welt of the stocking, with the result that the strands of silk are weakened in consequence of which a "run" is created.

While various attempts have been made from time to time to overcome this difficulty with varying degrees of success, none have been uniformly successful.

It is among the objects of the present invention to provide a stocking having a reinforced top to which hose supporters may be anchored at any point within an extremely wide area, this being of decided advantage over the present usual provision of reinforced garter blocks of limited area.

A further object of the invention is the provision of a stocking having the top thereof reinforced throughout its circumferential extent and further by the provision of means for lending to this reinforced portion a degree of elasticity which has not been obtainable heretofore.

A still further object of the invention is the provision in a stocking of a reinforced welt portion which is characterized in that it is provided with a plurality of circumferentially spaced areas of less reinforcement whereby not only to afford a pronounced degree of elasticity in the lower portion of the welt and particularly along the line between the welt and the web of the stocking, but also to generally enhance the appearance of the welt.

Other objects of the invention and advantages thereof will be apparent more fully hereinafter.

The invention consists substantially in the combination, construction, location and relative arrangement of the several parts of the stocking, all as will appear more fully here-

inafter, as shown in the accompanying illustrative drawing and as pointed out in the appended claims. In the said drawing, which is not intended to be restrictive but merely as illustrative of certain preferred forms of the invention:

Figure 1 is a perspective view of a stocking constructed in accordance with and embodying the present invention;

Figure 2 is a rear elevational view of the stocking shown in Figure 1; and

Figure 3 is a view of the upper portion of a stocking embodying the invention in a modified form.

Referring now to the drawing and more particularly to Figures 1 and 2 thereof, it will be observed that the stocking 10 is provided with the usual leg and foot portions 11 and 12 respectively. It is in the welt portion 13 of the stocking that the present invention resides, this welt portion being characterized chiefly by the provision therein of a plurality of triangularly shaped areas 14 of less reinforcement than the body of the welt.

In fabricating the stocking shown, the welt 13 is knitted of a heavier thread than is the web of leg portion 11, thereby providing a rather heavily reinforced portion extending circumferentially about the stocking and upwardly of the line 15 which separates the welt from the non-reinforced leg portion of the stocking. The upper part of the reinforced welt is doubled upon itself in such manner that the welt consists of a reinforced top section 16 of doubled thickness and a reinforced lower section 17 of single thickness. This lower section 17 is of sufficient strength to afford in any point thereof a firm and secure anchorage for the clasp of a hose supporter.

In order to provide the reinforced section 17 with sufficient elasticity so that it may comfortably fit the wearer, the areas 14 are provided. These areas 14 are circumferentially spaced about the welt of the stocking and while of less strength than the body 17 are nevertheless of greater strength than the non-reinforced web of the stocking leg 11. In the form of stocking constructed as

shown in Figures 1 and 2, these areas 14 are respectively of triangular shape and are so located that they extend upwardly into the section 17 with the bases thereof coincident 5 with the line 15.

It will be apparent that inasmuch as these areas 14 constitute a relatively small portion of the welt, there is little likelihood of accidentally anchoring the clasp of a hose supplier therein instead of in the more heavily reinforced portion of the welt. Not only does this feature materially reduce the liability of creating "runs" in the stocking but the provision of these less reinforced areas 15 affords a pronounced degree of elasticity along the bottom edge of the welt which is comparable favorably to that afforded in the non-reinforced leg portion of the stocking, thereby not only adding to the comfort of 20 the wearer but also effectually precluding the possibility of overstraining and so tearing the welt along the bottom edge thereof.

It will be understood of course that the present invention is not intended to be limited to the triangular shape of the areas 14 but instead may be of any other desired shape, as, for instance, the rectangular shape of the areas 14^a shown in Figure 3. The invention is susceptible of other changes from 30 time to time without departing from the general principles or real spirit thereof and it is accordingly intended to claim the same broadly as well as specifically as indicated by the appended claims.

35 What is claimed as new and useful is:—
1. In a stocking, a non-reinforced leg portion, a welt formed at the top of said leg portion, said welt being reinforced throughout and doubled upon itself in such manner 40 that the lower section thereof is of single thickness, and means formed in said lower section of the welt to lend elasticity thereto, said means comprising one or more spaced areas of relatively small extent and of lighter 45 reinforcement than that of the section in which the same are included.

2. In a stocking, a leg portion having a relatively heavily reinforced top section, and a plurality of triangularly shaped 50 blocks of relatively small extent formed in said top section with the bases thereof substantially coincident with the bottom edge of said section, said blocks being each provided with less reinforcement than that of 55 the remaining portions of the top section whereby to lend greater elasticity to said bottom edge.

In testimony whereof, I have hereunto affixed my signature.
